LIGHT FUEL INJECTOR

Filed June 3, 1944

UNITED STATES PATENT OFFICE

2,458,377

LIGHT FUEL INJECTOR

William Earl Hennings, Springfield, Mass.

Application June 3, 1944, Serial No. 538,657

5 Claims. (Cl. 103—41)

1

This invention relates to fuel injectors for internal combustion engines, of the type in which fuel is delivered under pressure to the combustion chamber of the engine.

One difficulty encountered in commonly used injectors and injector systems is the pollution of the lubricating oil in the base of the injection pump by the non-lubricating light fuel which, under compression leaks past the plungers of the injection pump, and, in some cases, the similar pollution of the lubricating oil in the base of the engine.

Among the objects of my invention are the overcoming of the above mentioned difficulties, and the securing of proper lubrication of the injector parts in a simple and reliable manner.

Other objects include an improved control of the injector and its operation and the details and arrangement of the parts, all of which will be made apparent in the following specification and claims.

In accomplishing the objects of the invention, I depart from the conventional constructions of the injector itself and the manner of its operation.

In the accompanying drawing which illustrates one embodiment of my invention,

Fig. 1 is a partly diagrammatic view, with parts in section, showing the general arrangement of the parts and elements in relation to an engine cylinder and to each other;

Fig. 2 is a longitudinal sectional view on a larger scale, of an injector, illustratively embodying certain features of the invention; and

Fig. 3 is a detail view, on a smaller scale of the high pressure injector control pump, looking from the left in Fig. 1.

Referring to Fig. 1, the fuel injector system is shown as generally comprising the fuel injector 10, mounted in the head of an engine cylinder 11, a fuel tank 12, connected by a feed line 13 to a fuel transfer pump unit which includes a filter 14 and diaphragm pump 15 of conventional design. The pump 15 connects by fuel line 16 to the injector 10. An oil supply tank is shown at 17 from which an oil supply line 18 leads to a low pressure pump 19 which supplies a high pressure pump 20 through a line 21. Surplus oil supplied to pump 20 by pump 19, is returned to tank 17, through a check valve 22 and line 23. A power line 24 connects the pump 20 to the injector 10.

Referring to Fig. 2 the injector 10 is shown as comprising a body member 25 formed with a cylindrical bore 26. Member 25 is provided at its lower end with an extension 27 of smaller diam-

2

eter through which a passage 28 opens to a recess or chamber 29. The upper end of member 25 is closed by a cap 30 threaded into the upper end of bore 26. Cap 30 is provided with a recess 31 in which is threaded a coupling member 32. Member 32 is formed with a passage 33 opening to a chamber 34 formed in member 32. Chamber 34 houses a check valve comprising a ball 35 held in position to close the inner end of passage 33 by a four prong spring 36. Passages 37, 38, 39 and 40 formed in cap 30 and member 25 connects chamber 34 with the bottom of bore 26. A movable wall member divides bore 26 into two chambers. As shown this member comprises a piston member 41 lap fitted to slide in the cylinder 26 and forming with the cylinder a fuel chamber 42 below the piston. The piston 41 is recessed at its upper end to form a fluid pressure chamber 43. A spring 44 positioned, in the form illustrated, in chamber 42, presses the piston 41 toward its upper position, as shown in Fig. 2. A passage 45 opens from chamber 43 through cap 30 and a coupling member 46 which may be formed integral with the cap.

25 An injection nozzle 47 provided with an atomizing jet discharge opening 48, is threaded on extension 27. The nozzle 47 is formed with an annular shoulder 49 which supports a four-prong spring 50 acting to press ball 51 into position to close passage 28 and form a spring loaded discharge valve between chamber 42 and the discharge opening 48. The nozzle 47 is exteriorly threaded at 53 for connecting the injector unit to the engine cylinder as shown in Fig. 2. As shown in the latter figure fuel line 16 is connected by a conventional coupling 54 to the coupling member 32 of the injector and pressure line 24 is connected by a similar coupling 55 to coupling member 46.

40 The piston 41 of the injector is operated by pump 20, as later more fully described by oil of a lubricating quality supplied under pressure to the chamber 43 through pump 20 and line 24 by the pump 19. Pump 20 is of the metering type. Various forms of metering pumps may be used subject to the modification of their operation to conform to the purpose of my invention as hereinafter pointed out. As shown, one form of such pump is indicated generally at 20 and comprises a housing 57 in the upper portion of which is formed a chamber or sump 58 which is maintained full of oil through line 21 by the pump 19. The pump 20 as will be understood is provided with a plurality of pistons, one for the injector of each cylinder of the engine, one of the

pump pistons being shown at 59. The piston 59 operates in a cylinder 60 to which ports 61 open from sump 58, when the piston is in its lower-most position, to admit oil to the cylinder 60 above the upper end of the piston. The lower end of the piston is provided with a shank 62 connected to a block 63 having on its lower face a groove 64 in which is mounted a cam roll 65, engaged by eccentric cam 66 secured to shaft 67. A spring 68, compressed between a web 69 of the housing and the block 63, maintains roll 65 in operative engagement with the cam 66. As will be obvious rotation of shaft 67 will effect reciprocation of the piston 59. The piston 59 is provided with a vertical groove 70 connecting its upper face with a circumferential groove having a helical upper edge 72, positioned to cross the port 61 as the piston 59 approaches or reaches the upper end of its stroke thus reducing the pressure of the oil in the power line 24 to that of the oil in the sump 58 which is the pressure maintained by pump 19 and valve 22. Piston 59 is rotatably mounted in its cylinder to permit adjustment of the helical edge 72 relative to port 61 and thereby adjust the duration of the power stroke of the piston. To effect this adjustment a gear 75 is rotatably mounted on the lower portion of cylinder 60 between webs 76 and 69 of the pump housing. A flange extending downwardly from gear 75 is provided with diametrically opposite vertical slots 77 in which the ends of a pin 78 carried by the piston shank 62 engage. The gear 75 is rotated by a rack 79 which is reciprocated by any suitable means. The shank 62 is connected to block 63 by a swivel 80, the block 63 being held against rotation in any suitable manner as by the engagement of the shaft of cam roller 65 in a groove (not shown) in the wall of the pump housing. In general, the construction of pump 20 as described follows a conventional form but for my purposes the usual check valve in the discharge port of the pump is eliminated. Check valve 22 in line 23 serves to maintain the oil in the sump 58 at or below the pressure of pump 19.

The cam shaft 67 is driven from the engine shaft through suitable timing gears, generally indicated at 83 in Fig. 3, and the several cams 66 for operating the pistons of pump 20 are positioned on shaft 67 so as to give the desired sequence of operation to the injectors of the several engine cylinders.

When the system is in operation fuel pump 15 transfers fuel from the fuel tank 12 to chamber 42 of the injector. The fuel pump may be driven from the camshaft of the engine or from shaft 67 of pump 20. The lubricating oil which is used as a hydraulic medium follows two circuits. The first is a low pressure circuit activated by the low pressure pump 19. The second is a circuit which is intermittently high and low pressure and is activated by pump 20. In the first circuit oil is transferred by pump 19 from the reservoir 17 to the sump 58 of pump 20. From the sump it flows through valve 22, which controls the oil pressure in the sump, and returns to the reservoir 17. It is to be noted that since the oil is always under pressure it will have no chance to develop air bubbles which are a frequent cause of trouble in fluid pressure operated systems. Once assembled as a unit and having the air properly bled from the lines my system should develop no air bubbles. In the second circuit the oil from the sump 58 which is under pressure from pump 19 and valve 22 will

enter cylinder 60 through the ports 61 when the piston 59 is in its retracted position and will fill the line 24 and chamber 43 of the injector. The pressure exerted by pump 15 on the fuel entering chamber 42 is less than the pressure of the oil in chamber 43 so that no light fuel can pass the injector piston 41 to contaminate the oil in chamber 43. The combined pressure of the fuel and spring 44 however is greater than the pressure 10 on the oil from pump 19 so that the injector piston 41 is held in its retracted position. When the drive shaft of pump 20 advances piston 59 the latter traps the oil above the ports 61 and acting through the oil filled line 24 increases the pressure in chamber 43 to an amount greater than the combined pressure of the fuel and spring 44. The injector piston 41 is therefore advanced against the pressure of the fuel and spring 44, closing check valve 31 and driving the trapped fuel in chamber 42 through the discharge valve 51 in the nozzle 47 and out through the spray jets 48 into the combustion chamber of the engine cylinder on which it is mounted. When the piston 59 of pump 20 finishes its power stroke, either by reaching the end of its mechanical stroke or by the metering operation of the helical edge 72, the pressure in chamber 43 falls to that maintained in sump 58 and the spring 44 causes the piston 41 to return to its retracted position, the oil in chamber 43 and line 24 flowing back into pump 20 as piston 59 retreats. At the same time the discharge valve 51 closes under the pressure of its spring 50 and fuel under the pressure of pump 15 opens check valve 35 and refills the fuel chamber 44 of the injector. The system is then ready for another fuel injection.

In the event that any oil has leaked past either piston 41 or piston 59 it is replaced by the operation of pump 19 which maintains a constant supply of oil in sump 58. Due to the fact that the pressure of spring 44 is always added to the pressure of the light fuel, the pressure of the lubricating oil can always be greater than the pressure of the light fuel so that in my system the piston 45 of the injector may be lubricated by the lubricating oil from the fluid pressure operating system and any leakage which can take place is of lubricating oil into the fuel which is the reverse of present systems.

50 Furthermore my system and the structure of the injector makes possible an improved flexibility of adjustments. The duration of the power stroke and therefore the duration of the fuel injection may be adjusted by adjustment of the metering element of the fluid pressure pump without recourse to the operating parts of the injector itself, and the pressure differentials in the system may be adjusted by varying the pressure exerted by spring 44 and the spring 85 of valve 22, either by the use of shims under the springs or by substituting springs of different strength. The action of springs 36 and 50 may be similarly adjusted.

I claim:

65 1. Fuel injection apparatus for internal combustion engines which comprises, a fuel injector having a moveable wall member, a fuel chamber at one side of said member for receiving fuel under pressure and a fluid pressure chamber at the opposite side thereof, a discharge opening 70 from the fuel chamber, a spring loaded discharge valve closing said opening, a spring acting against the piston in the same direction as does the fuel pressure, an independent oil supply for said fluid pressure chamber, pump means for maintaining the supply of oil to the fluid pressure chamber

and for maintaining the oil pressure in said chamber above the pressure of the fuel but less than the combined pressures of the fuel and the spring and a second pump acting on the oil supplied to the fluid pressure chamber to intermittently increase the pressure of the oil above the combined pressures of the fuel and the spring.

2. Fuel injection apparatus for internal combustion engines which comprises, a fuel injector having a piston, a fuel chamber at one side of the piston for receiving fuel under pressure and a fluid pressure chamber at the opposite side thereof, a discharge opening from the fuel chamber, a spring loaded discharge valve closing said opening, a spring acting against the piston in the same direction as does the fuel pressure, an independent oil supply for said fluid pressure chamber, pump means for maintaining the supply of oil to the fluid pressure chamber and for maintaining the oil pressure in said chamber above the pressure of the fuel but less than the combined pressure of the fuel and spring and a second pump acting on the oil supplied to the fluid pressure chamber to intermittently increase the pressure of the oil above the combined pressures of the fuel and the spring.

3. Fuel injection apparatus for internal combustion engines which comprises, a fuel injector having a piston, a fuel chamber at one side of the piston for receiving fuel under pressure and a fluid pressure chamber at the opposite side thereof, a discharge opening from the fuel chamber, a spring loaded discharge valve closing said opening, a spring acting against the piston in the same direction as does the fuel pressure, an independent oil supply for said fluid pressure chamber including a sump, an oil line connecting said sump and fluid pressure chamber, pump means for maintaining the supply of oil to said sump and for maintaining the pressure in the sump, line and fluid pressure chamber above the pressure of the fuel in the fuel chamber but less than the combined pressures of the fuel and spring, and a variable discharge metering pump acting on the oil in said sump to intermittently increase the pressure in said line and the fluid pressure chamber above the combined pressures of the fuel and spring.

4. Fuel injection apparatus for internal combustion engines which comprises, a fuel injector having a piston, a fuel chamber at one side of the piston for receiving fuel under pressure and a fluid pressure chamber at the opposite side thereof, a discharge opening from the fuel chamber, a spring loaded discharge valve closing said opening, a spring acting against the piston in the same direction as does the fuel pressure, an independent oil supply for said fluid pressure chamber including a sump, an oil line connecting said sump and fluid pressure chamber, a pump supplying oil to the sump, a spring loaded overflow

check valve in the sump for maintaining oil in the sump, line and fluid pressure chamber and at a predetermined pressure greater than the fuel pressure but less than the combined pressures of the fuel and spring, and a metering pump acting on the oil in the sump to intermittently increase the pressure in said line and the fluid pressure chamber above the combined pressures of the fuel and spring.

5. Fuel injection apparatus for internal combustion engines which comprises, a fuel injector having a piston, a fuel chamber at one side of the piston for receiving fuel under pressure and a fluid pressure chamber at the opposite side thereof, a discharge opening from the fuel chamber, a spring loaded discharge valve closing said opening, a spring acting against the piston in the same direction as does the fuel pressure, an independent oil supply for said fluid pressure chamber including a metering pump having an unchecked opening to the cylinder of the metering pump, an unchecked discharge line connecting the cylinder of the metering pump to the fluid pressure chamber, a pump supplying oil to the sump, a spring loaded overflow check valve in the sump for maintaining the oil in the sump, metering pump cylinder, said discharge line and fluid pressure chamber at a predetermined pressure greater than the fuel pressure but less than the combined pressures of the fuel and said spring, means for intermittently advancing the piston of the metering pump past the opening from the sump to the cylinder of the metering pump to trap the oil in the discharge line and fluid pressure chamber between the piston of the metering pump and the piston of the injector to increase the pressure of the trapped oil to an amount in excess of the combined pressure of the fuel and said spring.
